ENGRAVING AND COPYING MACHINE

Kurt Zwick, Munich, Germany, assignor to Fried-
rich Deckel, Munchen-Prinz-Ludwigshohe, Ger-
manyApplication March 28, 1936, Serial No. 71,483
In Germany April 2, 1935

34 Claims. (Cl. 90—13.1)

This invention relates to engraving and copying machines, using these words in a broad sense as including die sinking machines. It is highly desirable that such machines shall be able to produce work on the same scale or size as the pattern or model, and also on a reduced or enlarged scale, as occasion requires. Heretofore, however, no simple, convenient, and efficient machine for accomplishing this has been devised.

5 Satisfactory machines are known in which work may be reproduced on the same scale or size as the pattern or model, but in which reduction or enlargement is not possible. Also, satisfactory reducing and enlarging machines have been produced, but on these, reproduction on an equal scale is not possible. It has also been proposed to construct machines so that equal scale work and also reduction or enlargement work is possible, but these machines have been unsatisfactory for various reasons. In all cases, the model or pattern has had to be either turned through 180° with respect to the work, or has had to be a complementary reversed or mirror-like pattern, or else either the work or the pattern has had to be mounted to move during operation. When the pattern is turned through 180° relatively to the work, any given movement of the tool operating upon the work must be produced by a movement in the opposite direction of the hand guiding the tracer point, and this reversal of motion is inconvenient. The use of a reversed or mirror-image pattern is inconvenient and impractical in many cases. Frequently, also, in such machines, and particularly in machines where the pattern is turned through 180° relatively to the work, the pattern has been located so far from the work that it has been impossible or difficult for the operator to observe simultaneously the pattern and the work as the reproduction operation proceeds. A machine in which either the work or the pattern must move during operation, is unsuited to heavy and large work pieces or patterns, since in such cases the great weight of the necessary movable parts makes the movements difficult.

30

40

45

An object of the invention is the production of a generally improved and more satisfactory engraving machine, or copying machine, or a machine for both engraving and copying, which is free of the objections above noted.

Another object of the invention is the provision of a machine in which the work may be reproduced either on the same scale or on an enlarged or reduced scale, and in which the pattern is similar to the work and oriented in the same direc-

tion as the work, instead of being a reversed mirror image pattern or a pattern turned 180° relatively to the work, and in which both the pattern and the work may remain at rest on a stationary support, during operation, so that large and heavy work pieces or patterns may easily be used.

Still another object is the provision of such a machine in which the pattern and the work may be placed closely adjacent to each other for simultaneous observation by the operator.

A further object is the provision of such a machine in which more than one reproduction can be made at the same time by a single tracing of the same pattern, under many circumstances.

10 A further object is the provision of a machine of this character so constructed that when the reduction or enlargement ratio is changed during the making of a single engraving or copy, the engraving or copy being made may remain clamped in its fixed position on the work table and need not be shifted as a result of the change in the ratio.

15 A still further object is the provision of a machine particularly suitable for relief work, such as the making or "sinking" of various kinds of dies, and more especially of a machine in which the movements of the tracing point and of the cutting tool may be entirely perpendicular to the surfaces of the pattern table and the work table, notwithstanding differences in elevation of the different parts of the pattern and work.

20 To these and other ends the invention resides in certain improvements and combinations of parts, all as will be hereinafter more fully described, the novel features being pointed out in the claims at the end of the specification.

25 In the drawings:

Fig. 1 is a diagrammatic plan view of one form of apparatus constructed in accordance with certain features of the present invention;

Fig. 2 is a diagrammatic side elevation of the apparatus shown in Fig. 1;

Fig. 3 is a view similar to Fig. 2 of a slightly modified form of apparatus;

Fig. 4 is a side elevation, somewhat diagrammatic, of a machine constructed in accordance with a different embodiment of the invention;

Fig. 5 is a view similar to Fig. 4 showing still another embodiment of the invention;

Fig. 6 is a diagrammatic plan view of the apparatus shown in Fig. 5;

Fig. 7 is a front elevation of a machine constructed in accordance with a preferred embodiment of the invention;

Fig. 8 is a side view of the machine shown in Fig. 7;

Fig. 9 is a side view with parts in vertical section of the machine shown in Figs. 7 and 8, viewed from the opposite side from that shown in Fig. 8, the section being taken approximately on the line IX—IX of Fig. 10;

Fig. 10 is a plan of the machine shown in Figs. 7 and 8;

Fig. 11 is a vertical section taken substantially on the line II—II of Fig. 10;

Fig. 12 is a vertical section through a cutting tool spindle used on the machine of Figs. 7 and 8, and associated parts;

Fig. 13 is a horizontal section taken substantially on the line I3—I3 of Fig. 12, and

Fig. 14 is a vertical section through one form of spindle driving mechanism.

The same reference numerals throughout the several views indicate the same parts.

At the outset it may be convenient to explain that engraving and copying machines frequently employ a pantograph system. The term "pantograph" has often been rather loosely applied to denote two widely different types of linkages, and this has caused some confusion. For example, the type of linkage illustrated in Fig. 3 of my United States Patent No. 1,972,910, granted September 11, 1934, is often referred to as a pantograph. This type of linkage is suitable only for making reproductions of the same scale or size as the model or pattern, and is not used for producing a reduction or enlargement of the scale. For convenience, and to avoid confusion with the other type of pantograph linkage, this type shown in my said patent may be referred to as a parallelogram linkage or a pantograph of the parallelogram type.

The other type of linkage to which the term "pantograph" has frequently been applied, is a linkage such as that illustrated in Fig. 4 of United States Letters Patent No. 1,754,256, granted April 15, 1930, for an invention of Lorenz K. Braren. This type of linkage is suitable for reduction or enlargement, but is not suitable for reproductions of the same scale or size as the model or pattern, unless the tracing point be placed on the opposite side of the fixed pivot from the cutting tool, which is often inconvenient and unsatisfactory. For convenience, and to distinguish this type of linkage from the one previously mentioned, the linkage shown in said Braren patent may be referred to as a storksbill or lazytongs linkage or a pantograph linkage of the storksbill or lazytongs type.

Those skilled in the art will readily appreciate the fundamental distinctions between these two types of linkages. The terms used in the above description will be employed throughout the specification and claims, as occasion requires, to distinguish the two types of linkages from each other.

Referring now to the first embodiment of the invention illustrated diagrammatically in Figs.

1 and 2, there is provided a pantograph linkage of the lazytongs type, made up of members 21, 22, 23, and 24, joined to each other preferably in an adjustable manner, such as that disclosed in said Braren patent, the member 21 being pivoted to the frame of the machine on the fixed vertical pivot. The arm 22 carries a socket or holder 26 in which may be inserted either a tracing point or a cutting tool (preferably a rotary cutting tool driven by a suitable motor) which may cooperate with a pattern or work placed on the table 27.

A beam 30 is slidable longitudinally along guideways on a U-shaped member 31 having legs 32 slidable in fixed guideways 33 extending in a direction substantially perpendicular to the beam 30. Thus the beam 30 is movable in one direction in a horizontal plane by movement along its U-shaped support 31, and movable in another direction at right angles thereto by moving the whole support 31 in and out relatively to the guides 33. In other words, the beam 30 is universally movable (within reasonable limits) in its own horizontal plane, and maintains always a position parallel to itself; that is, each position that it can occupy is parallel to every other position that it can occupy, so that when the beam 30 is moved, every part of the beam partakes of the same movement of identical extent and direction. In other words, the beam is capable of motion of translation but is restrained against motion of rotation.

This beam 30 carries two or more sockets 35 and 36, similar to the socket 26, so that either socket may receive the tracing point or a cutting tool, at will, which tracing points or cutting tools are adapted to cooperate with patterns or work placed upon the holding tables 37 and 38.

At the point 39, on a direct line between the holder 26 and the fixed pivot 25, the lazytongs linkage is connected to the beam 30. Thus, whenever the point 26 of the lazytongs linkage is moved, the point 39 thereof is correspondingly moved by a proportionately smaller amount depending on the setting of the pantograph linkage, and since the point 39 is directly connected to the beam 30, it causes corresponding movement of the beam 30. Thus the sockets 35 and 36, and any cutting tools held in either or both of these sockets, partake of the same movement as the point 39 of the lazytongs linkage, namely, a movement corresponding to but in reduced scale relatively to the movement of the point 26.

It is now apparent that if a tracing stylus be inserted in the socket 26 and cutting tools in one or both of the sockets 35 and 36, the movement of the tracing stylus over a pattern or model will cause a corresponding reproduction of the pattern or model, on a reduced scale, on work placed upon the tables 37 and 38. If enlargement is required instead of reduction, the tracing stylus can be placed in either of the sockets 35 and 36, while the cutting tool is placed in the socket 26. When reproductions on the same scale are desired, without either enlargement or reduction, the tracing stylus is placed in one of the sockets on the beam 30 (for example, the socket 35) and the cutting tool is placed in the other socket on the beam 30 (for example, the socket 36). For such equal scale reproductions, the lazytongs linkage may be entirely disconnected from the beam 30 if desired, but frequently it is convenient to leave it connected to the beam and to use a suitable holder in the socket 26 as a handle by which to operate the linkage to move the beam 30 with less force than would be required if the force were applied directly to the beam.

It is now seen that with this arrangement, a machine is provided which is capable of reducing and enlargement operations, and also capable of equal scale or 1:1 reproductions. It is also seen that when equal scale reproductions are being made, the pattern and the work are placed close beside each other where they may conveniently be observed simultaneously during the progress of the work. Also, when reductions or enlargements are being made, the pattern and the work

- are close to each other, both on the same side of the fixed pivot 25 of the lazytongs linkage, so that they may be conveniently observed, and it is especially pointed out that in all cases the pattern and the work correspond with each other and are faced or oriented in the same direction, so that it is not necessary to have the pattern turned 180° relatively to the work, nor to have the pattern of reversed or mirror-image form.
- 10 In Fig. 3 of the drawings is shown a slight modification of the structure above described. Here, instead of connecting the point 39 of the lazytongs linkage directly to the beam 30, the point 39 is pivoted to a block 40 which may be clamped in any desired position along a bar 41 secured to the beam 30 and extending in a transverse direction thereto. The advantage of this construction is that when the adjustment of the lazytongs linkage is changed, to change the ratio 15 of reduction or enlargement, the member 40 may be loosened and shifted to a new position on the bar 41, leaving the bar 41 and the beam 30 in an unchanged position, so that the work need not be shifted to a new position.
- 20 25 If the guides 33 along which the U-shaped member 31, 32 moves are fixed in stationary position relatively to the machine frame, it will be apparent that the machine will be limited in its usefulness to flat or approximately flat engraving or copying work. A modified form of construction, which may be used also for relief work, has therefore been devised, and is illustrated somewhat diagrammatically in Fig. 4 of the drawings, to which reference is now made.
- 25 30 This machine comprises a frame 45 carrying tables 27a and 37a corresponding to the tables 27 and 37 in the embodiment previously described. Pivoted to the frame 45 by means of a substantially horizontal pivot shaft 46, is a carrier 47. 35 This carrier contains the guides 33a in which the arms 32a of the U-shaped member 31a may move. The beam 30a is slidably mounted on the U-shaped member 31a. The carrier 47 also has a substantially vertical pivot 25a, forming the fixed point of the lazytongs linkage, comprising the bars 21a, 22a, 23a, and 24a, which linkage has a socket 26a for receiving either a tracing point 48 or a cutting tool, as desired, and the beam 30a has one or more sockets 35a for receiving a tracing point or a cutting tool 49, as desired. The lazytongs linkage is connected as before, at the point 39a, to a block 40a which may be clamped in any desired position on the bar 41a secured to the beam 30a.
- 35 40 This construction differs from that described in connection with Figs. 1 to 3, inclusive, only in the fact that the lazytongs linkage pivot 25a and the guides 33a for the U-shaped member are both mounted on the carrier 47 movable about the horizontal shaft 46, instead of being mounted on fixed parts of the frame, and most of the parts of the embodiment illustrated in Fig. 4 are indicated by the same reference numerals used in Figs. 1 to 3, inclusive, with the addition of the letter "a". It will be seen that when the tracing point, mounted for example in the socket 26a, traces over a pattern in high relief, the upward and downward movements of the tracing point will simply rock the carrier 47 slightly about its horizontal pivot 46, and this in turn will cause rocking of the arms 32a of the U-shaped member 31, carrying the cutting tool 49 upwardly or downwardly to the proper extent to reproduce, in the work, the relief formation of the pattern or model.
- 45 50 55 In order to obtain an exact ratio equivalence

between the model and the work, the end of the tracing stylus 48 and the end of the cutting tool 49 should both lie exactly in a common plane passing through the axis of the shaft 46, as indicated by the dot-dash line 50, and the axis of the fixed pivot 25a of the lazytongs linkage should also pass directly through the axis of the horizontal pivot 46, as indicated by the dot-dash line 51.

A further embodiment of the invention, exhibiting various improvements over the forms above described, will now be disclosed with particular reference to Figs. 5 and 6 of the drawings.

In these figures, the machine frame is indicated at 45b, and it carries pattern and work 10 tables 27b, 37b, and 38b, corresponding to tables 27, 37, and 38, previously described. The frame 45b has a horizontal pivot 46b on which is pivoted the carrier 47b in which is mounted the vertically fixed pivot 25b of the lazytongs linkage system, the parts of which may be identical with the lazytongs system described in connection with Figs. 1 to 3, inclusive, and which parts are indicated by the same reference numerals used for the corresponding parts in Figs. 1 to 3, 15 20 25 with the addition of the letter "b" to each numeral. In this embodiment, the lazytongs linkage is connected as before, at the point 39b, to the member 40b capable of being clamped in any desired position along the bar 41b mounted 30 on the beam 30b capable of universal movement of translation but remaining always parallel to itself. This mounting of the beam 30b for a movement of translation without any movement of rotation may be accomplished by the use of a 35 U-shaped member such as the member 31, 32 previously described, or it may be accomplished by mounting the beam 30b on a linkage of the type above referred to as a parallelogram linkage. The mounting is here shown, by way of 40 example, as a parallelogram linkage mounting, including the bars 55 and 56 pivoted at their right hand ends to the beam 30b and extending parallel to each other and pivoted at their left hand ends to the bars 57 and 58 respectively, 45 which are also parallel to each other and which are pivoted to the member 59. A bar 60 connects the joint between the bars 55 and 57 to the joint between the bars 56 and 58. With this type of linkage, it is seen that the beam 30b may 50 move horizontally in all directions, as required. As before, the beam carries two or more sockets 35b and 36b, in each of which either a tracing stylus or a cutting tool may be placed, as required.

The member 59, to which the parallelogram linkage carrying the beam 30b is pivoted, is mounted for vertical movement along a vertical guideway 62 on the frame 45b of the machine. The weight of the member 59 and of all parts 60 supported therefrom is counterbalanced by means of a counterweight 64 connected to the member 59 by a cord or band 65 passing over a pulley 66 mounted on the machine frame. Preferably also there is another pulley 67 below the pulley 66, 65 and a cord or band 68 of adjustable length passes downwardly from the counterweight 64, around the pulley 67, and up to a connection with the member 59, so that the mass inertia of counterweight 64 may be utilized for the attenuation or damping of the vertical vibrations of the tool holder and other parts directly or indirectly carried by the member 59.

An arm 70 is pivoted at one end, by means of a vertical pivot, to the beam 30b, and at the 75

other end is pivoted, by a vertical pivot, the arm 11 which carries the socket 12 in which may be placed either a tracing stylus 13 or a cutting tool, as required. The tool or stylus is mounted so as to be vertically slideable through the socket 12. The upper end of the tracing stylus is pivotally connected at 14, as by means of a universal joint, to a member 15 fixed to the lazytongs linkage in a position corresponding to that of the point 26. A handle 16 may be provided for convenience in guiding the stylus over the pattern.

With this arrangement, relief work can be efficiently done, and yet at all times the tracing point 13 and the cutting tool 49b will remain strictly perpendicular to the surfaces of the tables 27b and 37b, with greater ease in cutting vertical surfaces, and as distinguished from the arrangement shown in Fig. 4, in which a raising or lowering of the tracing stylus and cutting tool results in a slight tilting of the axis of the stylus and tool relatively to the tables 27a and 37a, throwing them out of a true perpendicular position. In the improved arrangement of Figs. 5 and 6, when the stylus 13 moves up, it slides vertically through the guiding socket 12 which remains always vertical by reason of the vertical pivots of all of the linkage bars between the socket 12 and the member 59. The raising of the stylus 13 raises the member 15 on the end of the lazytongs linkage, thus tilting the lazytongs linkage upwardly and swinging it around its horizontal pivot 46b. This upward tilting of the lazytongs linkage pulls upwardly to a corresponding but reduced extent on the member 40b fastened to the bar 41b, and thus pulls upwardly on the beam 30b, raising the entire parallelogram linkage and member 59, which may move vertically very easily because of the counterbalancing effect of the counterweight 64. The vertical movements of the tracing stylus thus result in true vertical movement of the cutting tool, even though the lazytongs linkage is tilted about its horizontal axis 46b.

The same thing holds true if the positions of the stylus and cutting tool be reversed, when it is desired to make enlargements rather than reductions. In that event, the cutting tool is slideable vertically through the socket 12 and is connected through the universal joint 14 to the lazytongs linkage part 15, which controls or produces the upward and downward movements of the cutting tool. For reproductions on an equal scale, the cutting tool and the tracing stylus are both mounted in the sockets on the beam 30b. The lazytongs linkage then may be disconnected from the beam or, preferably, is used for operating the beam in the desired manner by a smaller force than would be required if the force were applied directly to the beam.

In connection with exceptionally difficult work, such as the milling of dies and the like, it is advisable to transmit the thrusts as directly as possible from the tracing point to the tool holder. This may be facilitated if the bar 41b is not fixed immovably on the beam 30b, but is movable to different positions along the beam, as by being mounted on dove-tail guides as shown in Fig. 5. A clamping screw or other suitable means is provided for holding the bar in any desired position on the beam. Hence, when only one cutting tool is in use, the bar 41b can be shifted along the beam 30b to a position close to that cutting tool, and when two cutting tools are in use, the bar 75 may be centered midway between them.

The use of the bar 41b, as previously explained in connection with Fig. 3, permits a change of the reduction or enlargement ratio during the progress of the work, without the necessity of unclamping and resetting the work in a new position 5 on the work table.

To insure accuracy of reduction or enlargement, the axis of the vertical pivot 25b should intersect the axis of the horizontal pivot 46b, as shown by a dot-dash line in Fig. 5, and the 10 universal joint 14 between the members 13 and 15 should lie in a line drawn through the axis of the horizontal pivot 46b and through the pivot connecting the member 39b to the member 40b, as indicated by another dot-dash line in Fig. 5. 15

A preferred embodiment of a complete engraving and copying machine, employing the main principles of the embodiments previously disclosed, and also having further advantageous features, will now be described with reference to 20 Figs. 7 to 14, inclusive.

The machine comprises a main frame or standard 101 on which are mounted the tables 102 and 103, each having suitable slots, such as T-shaped slots, by means of which the pattern 25 and work may be conveniently clamped to the tables. The table 102 is mounted on a slide 104 movable horizontally along guideways on a slide 105 which is movable vertically along guideways on the frame 101. A screw controlled by the 30 handle 106 serves to move the table 102 horizontally, while another screw or other suitable mechanism controlled by the handle 107 serves to move the table vertically.

The other table 103 is movable horizontally 35 along guideways on a slide 110 which is likewise movable horizontally along guideways at right angles to the first mentioned guideways, on a slide 111 which is movable along vertical guideways on the frame 101. A feeding screw or other 40 suitable mechanism controlled by the handle 112 serves to move the table 103 horizontally in one direction, while a feeding screw or other suitable mechanism controlled by the handle 113 moves the table 103 horizontally in the direction at right 45 angles thereto, and a screw or other suitable mechanism controlled by the handle 114 moves the table vertically.

Suitable graduations are preferably associated with each of the feeding handles 106, 107, 112, 113, and 114, in order that the tables may be quickly set to any desired position or moved through any predetermined distance. The vertical slides 105 and 111 preferably also carry pointers or index markings 116 and 117, respectively, which cooperate with a scale 118 fixed to the frame 101, so as to show the respective heights of the top surfaces of the two tables. The table 102 may conveniently be referred to as the pattern table and the table 103 as the work 60 table, although in some circumstances the pattern is placed on the table 103 and the work is placed on the table 102, as, for example, when making a reproduction on an enlarged scale.

Near the top of the main frame 101 is a member 120 accurately guided in vertical guideways so that it may move upwardly and downwardly relatively to the main frame. This vertically movable member 120 carries a pair of horizontally arranged and forwardly projecting guideways 121 on which are slidably mounted the side arms 122 of a U-shaped frame, which side arms are rigidly connected to each other by the cross bar 123. Ball bearings are preferably interposed between the members 121 and 122 so that the U- 71

- shaped assembly carrying the bar 123 may move horizontally with great ease. This bar 123 may also move upwardly and downwardly, of course, carrying with it the members 120 and 121. The forward ends of the members 121 and 122, where they project beyond the member 120, are preferably enclosed by an accordion pleated bellows 124, to protect the guideways between the members 121 and 122 from dust, dirt, and the like.
- 5 A beam 125 is movable on horizontal guideways (preferably provided with ball bearings as indicated in Fig. 9) formed on the bar 123. Thus the beam 125 may move horizontally in one direction along its guideways on the bar 123, and 10 it may move horizontally in a direction at right angles thereto by moving the entire bar 123 inwardly or outwardly on the guideways 121, and it may move vertically by moving the entire guideways 121 and member 120 in a vertical direction along the frame 101. The beam is thus 15 capable of a universal movement of translation in any direction to any extent (within the limits of the machine) but is restrained by the guideways against any movement of rotation, so that 20 all positions which the beam 125 may assume are strictly parallel to each other.
- The beam 125 carries a plurality of sockets 25 two of which are shown at 127 and 128, respectively, and all of which sockets are adapted to receive interchangeably, as desired, either a rotary cutting tool or a tracing stylus. One or more of the sockets may be adjustable horizontally to various positions along the beam 125, horizontally extending guideways 129 (Figs. 7 and 9) 30 being provided in the beam 125 for this purpose.
- An arm or link 131 is pivoted at one end to the beam 125 by means of a vertical pivot 132, which may conveniently be attached to the holder or socket 128, instead of being secured immovably to the beam 125. The opposite end of the arm 131 is pivoted by another vertical pivot 133 to one end of the arm 134, the other end of which is provided with a socket 135 the purpose of which will be explained hereafter. By reason of 35 the vertical arrangements of the pivots 132 and 133, the linkage formed by the arms 131 and 134 is freely flexible in a horizontal direction, and the socket 135 may, therefore, be moved freely to any desired position in a horizontal direction, but 40 the linkage is perfectly rigid in a vertical direction and the socket 135 is therefore held in a strictly vertical position at all times, even though it may move up and down relatively to the frame 101, when the beam 125 moves up and down.
- 45 Substantially at the top of the main frame 101, above the member 120, is a horizontal clamping slot 140, and a block 141 may be moved along this slot and clamped in any desired position relatively thereto. This block 141 carries a horizontal pivot 142 (Fig. 8) on which is pivoted a carrier 143 having a vertical pivot 144 forming the main or fixed pivot of a lazytongs pantograph system or linkage. The lazytongs linkage 50 may comprise, for example, the arms 146, 147, 148, and 149 pivoted to each other by vertical pivots in the usual lazytongs pantograph manner, one of the arms (such as 149) being adjustable to different positions along its companion arms (such as 147 and 148) in order to set the lazytongs linkage for different ratios of reduction or enlargement. A member 155, settable to different positions along the arm 149, carries a vertical pivot 156 which extends downwardly below the bottom of the member 155 as shown in 55 Fig. 9, and is connected to a horizontal pivot 157

in a bracket 158 which may be moved to and clamped in any desired position along a horizontal guideway on a bar 159 secured to the top of the beam 125 and extending horizontally in a direction transverse to the length of the beam, as indicated in Fig. 10. This bar 159 may be fixed immovably in a given position on the top of the beam 125, is desired, but preferably it is movable to any desired position along a clamping groove 160 formed along the top of the beam 125, and when shifted to the desired position, the bar 159 may be clamped in such position by any suitable means such as the bolt 161 (Fig. 9).

At the outer end of the lazytongs arm 147 is a downward projection 165 connected through two pivots at right angles to each other, forming a universal joint, indicated generally at 166, to the upper end of a tube 167 which is slideable vertically within the holder 135 on the arm 134. This tube 167 is thus guided by the holder 135 so that 20 it is maintained always in a strictly vertical position, and the universal joint 166 permits this vertical position of the tube notwithstanding a tilting and a swinging of the member 165 and the other parts of the lazytongs linkage about the 25 horizontal axis 142, and the vertical axis 144, during operation. The tube 167 forms a socket for receiving a cutting tool spindle assembly, the universal joint 166 being made sufficiently large so as to accommodate a tool spindle driving pulley 30 168 without interference. The lower end 169 of the spindle is adapted to receive interchangeably, as desired, either a tracing stylus or a cutting tool, indicated at 170. When a tracing stylus is used, there is, of course, no belt connected to the 35 pulley 168, so that the spindle does not revolve, but when a cutting tool is used, the pulley 168 is suitably driven by a belt and the tool revolves in the usual manner.

In order to support the weight of the vertical 40 slide 120 and all other parts supported therefrom, counterweight or spring means is provided within the machine frame. As shown in Fig. 9, this means may conveniently be in the form of a spring 180 having its lower end secured to a 45 screw 181 having a nut 182 connected to a disk 183 which may be turned by means of pins 184, so as to vary the tension of the spring 180. The upper end of the spring is connected to a cord, or, preferably, a steel band 186, which is secured 50 to and runs over a pulley portion 187, the periphery of which is of a radius gradually increasing in an upward direction, as shown. The rate of increase of the radius of this pulley portion is so chosen with respect to the characteristics of the 55 spring 180 that the product of the force of the spring at any given degree of extension thereof times the radius of the pulley portion at the point where the band 186 is tangent to it, is a constant. By this means, the spring 180 exerts a constant 60 force tending to turn the pulley, rather than a force which is variable when the spring is stretched to a greater or less degree.

The pulley portion 187 is rigidly connected to another pulley portion 188 of uniform radius, to 65 which is attached a band 189 extending upwardly and running over an idler pulley 190 and thence downwardly to a point 191 where it is connected to the slide 120. Thus, by properly adjusting the spring tension by means of the nut 182, the spring 70 can be set so as to counterbalance exactly the weight of the slide 120 and all other parts supported thereby, and the slide 120 can be moved upwardly and downwardly along the frame 101 with great ease since the force tending to lift 75

the slide 120 is constant irrespective of the movements of the slide.

In order to limit the downward movement of the slide 120 to any desired extent, there is provided a rotatable member 195 accessible on the top of the frame 101 and suitably graduated so that this member may be set in any predetermined position. A long screw 196 is connected to and depends from this rotatable member or head 195 which screw passes into a socket in the slide 120 and is there provided with a nut 197 which can slide vertically in the socket of the slide 120, but which can not turn therein, the nut and socket being made non-circular or else the nut having a pin projecting into a vertical slot in one side of the socket. A ring 198 fixed to the slide 120 surrounds the screw 196 above the nut 197 but does not engage the screw threads of the screw so that the screw is freely slideable vertically through this ring. Slide 120 and associated parts may, therefore, move downwardly until the ring 198 comes to rest on the top of the nut 197, but may not move any farther, and the elevation at which this contact between the parts 197 and 198 takes place may be adjusted by turning the head 195. This serves as a depth limiter.

As previously mentioned, the sockets 127 and 128 on the beam 125 may be so constructed that they may receive either a cutting tool or a tracing stylus, at will. The construction may be such that the whole cutting tool spindle may be removed when not needed, and a tracing stylus may be substituted therefor. On the other hand, if preferred (as is often the case) the cutting tool spindle may remain permanently in the socket 127 or 128, and the cutting tool may simply be removed from the end of the spindle when not needed, and be replaced by a tracing stylus secured to the spindle, the driving of the spindle being omitted, of course, when the cutting tool is not used.

A preferred arrangement of cutting tool spindle, remaining in place within the socket, is indicated in Figs. 12 and 13. Here, the socket or holder 121 is indicated, but it is obvious that the same construction may also be used for the socket 128 or any other tool spindle sockets of this machine. Fixed in the upper end of the socket 127 is a sleeve 201 having suitable bearings 202 (preferably ball bearings) for holding a rotatable tube 203, the upper end of which is provided with a driving pulley having belt grooves 204 and 205.

Vertically slideable in the lower part of the socket 127 is a sleeve 207 having ball bearings 208 and 209 for supporting a rotatable spindle 210. The spindle is connected to and driven from the rotating tube 203 by means of an upward extension 211 at the top of the spindle 210 which extension is of non-circular cross section, as shown especially in Fig. 13, and which fits slidably into a similarly shaped part at the bottom of the tube 203. Thus the sleeve 207, spindle 210, and extension 211 may slide upwardly and downwardly relatively to the sleeve 201 and 203, but the spindle is at all times operatively connected to and driven from sleeve 203. At the lower end of the spindle 210 is a socket which may receive, as desired, either a cutting tool 215 or a tracing stylus, either of which may be clamped in the spindle socket by suitable means, such as a collet or split collar 216 and a clamping nut 217.

In order to control the vertical movements of the sleeve 207 and spindle 210 within the holder 121, there is provided a pin 220 secured to the sleeve 207 and projecting outwardly through a

slot 221 in one side of the holder 121 to an accessible external head which may be grasped when desired to raise or lower the spindle. Intermediate its length, the pin 220 passes through a vertical member 223 slideable vertically through a bore in an extension on the holder 121. The lower end of this member 223 is hollowed out to form a cavity in which is placed a spring 224 pressing at its upper end against the member 223 and reacting at its lower end against a cap 225 threaded into the holder 121. Thus the spring constantly tends to raise the member 223 and with it to raise the sleeve 207 and spindle 210.

The upper end of the member 223 is in the form of a screw threaded shank 227 which is engaged by screw threads on the inner surface of a sleeve 228 having an accessible head 229 which may be turned for purposes of adjustment. This threaded sleeve 228 is rotatable within, but held against vertical movement relatively to, a second sleeve 230 which is slideable vertically in the above mentioned bore in the holder 121, and which may be held in any desired vertical position by tightening a clamping nut 231 to reduce slightly the diameter of the bore in which the sleeve 230 is movable.

By this construction, when the clamp 231 is clamped to hold the sleeve 230 against vertical movement, the head 229 may be rotated to turn the sleeve 228 relatively to the screw threads 227, and thus to raise or lower the tool spindle slightly in order to place the tool exactly in the right position relatively to the work. When the tool has been properly located, it may be maintained in this position by tightening a clamp 232 which has the effect of clamping the sleeve 207 immovably in the holder 121. If it is desired to raise the tool for a while and later return it to exactly the same position, this may be done by loosening the clamps 232 and 231, so that the spring 224 will raise the sleeve 207, the sleeve 230 then rising in its bore. To return the spindle to its previous position, downward force is applied to the cap 229 or pin 220 or both, pushing these parts downwardly until an annular flange at the top of the sleeve 230 rests upon the surface at the top of the bore in which this sleeve is received. Then the clamps 231 and 232 are tightened, or, if further adjustment is desired, the clamp 231 is tightened and the clamp 232 is left loose, after which the head 229 may be rotated to produce such further adjustment as required.

For driving the tool spindles, an electric motor 240 may be secured to one side of the machine frame 101. At the upper end of the armature shaft of this motor is a pulley 241 over which a driving belt may pass to a second pulley 242 mounted on a bearing on an arm 243 slideable longitudinally along a housing 244 which has a bearing 245 concentric with the pulley 241 so that the housing may swing horizontally to any desired position around the pulley 241, but is restrained against any tilting movement, so that the housing 244 acts as a cantilever and supports the weight of the pulley 242 and other parts. A clamp 246 serves to hold the sliding member 243 in any desired position to produce the proper tension on the belt 247 running from the pulley 241 to the pulley 242.

The pulley 242 is secured to a sleeve 248 which extends downwardly from the pulley and to which is secured a second pulley 249 over which may run a belt 250 extending to the pulley 204, 205 on the tool spindle. A housing 252 surrounds the belt and runs from the pulley 241 to the pulley

204, 205, not only protecting the belt, but also exerting the necessary force to resist or counter-balance the tension of the belt 250. Because of the fact that, during operation, the tool spindle 5 may move vertically to a considerable extent relatively to the motor 240, this housing 252 must be connected in such a manner as to permit such rising and falling movement of the spindle. One end of the housing is, therefore, pivotally connected to a sleeve member 253 surrounding and rotatable upon the sleeve 201 of the spindle, by means of pivot pins 254 (Figs. 12 and 14) extending generally transversely to the length of the housing 252, so that this housing may tilt about 15 these pins 254 as an axis. A member 256 is slideable longitudinally along the housing and may be clamped in any desired position by means of the clamp 257. This member 256 is engaged with the lower end 258 of the shaft on which the pulleys 242 and 249 are mounted, by means of a spherical bearing 259, so that the housing 252 may tilt laterally as well as longitudinally, or in any desired direction, relatively to the shaft 258, although the housing is at all times supported by this shaft. Thus the housing forms a connection between the tool spindle shaft and the pulley shaft 258 which is flexible in a vertical direction but rigid in a horizontal direction, so as to maintain the tension on the belt 250. As 20 the tool spindle moves horizontally over the work, this results, of course, in horizontal movement of the pulley shaft 258, turning this shaft about the motor shaft as a center.

When a tool is used at the position 170 so 35 that it is necessary to drive the pulley 160 to drive the spindle within the tube 167, then a belt is run from the pulley 168 to a special groove 262 on the pulley 242, and the housing 252 is removed and replaced by a rod-like spacer connected 40 on the one hand to the member 256, and on the other hand to a suitable part of the spindle tube 167.

From what has previously been said, it will be understood by those skilled in the art that when a 45 reproduction on a reduced scale is to be made, the pattern may be placed upon the table 102 and the work may be placed upon the table 103. A tracing stylus 170 is then mounted in the tube 167, and a cutting tool 215 is mounted on the 50 spindle 210 within the holder 127. If the reproduction be a die or other work in relief, the upward and downward movements of the tracing stylus 170 will cause the lazytongs linkage to tilt upwardly and downwardly about its horizontal pivot 142, and these vertical movements will be correspondingly transmitted, though on the proper reduced scale, from the lazytongs system 55 through the pivot connection 156, 157, to the beam 125 on which the cutting tool 215 is mounted. Horizontal movements of the tracing stylus 170 in any desired position will likewise be transmitted through the connection 156, 157, to the beam 125, which will thus at all times move in exactly the same direction as the tracing stylus 60 170, but on the proper reduced scale, depending upon the setting of the lazytongs linkage.

If part of the work is to be reproduced on one scale and another part of the same piece of work on a different scale, a change of scale during 65 progress of the work may be accomplished without having to shift the work on the table, by loosening the clamping nut of the member 158 and sliding it along its guideway on the bar 159 at the same time that the setting of the lazytongs linkage is adjusted by moving the bar 149 to a

new position along the bars 147 and 148 and by moving the member 155 to a new position along the bar 149, keeping the members 165, 156, and 144 always in a straight line with each other.

On very large work, where it is desired to increase the distance between the tool and the tracing point as much as possible, the whole lazytongs linkage system may be moved laterally by shifting the member 141 along the guideway 160, and by correspondingly shifting the bar 159 along its guideway 160 on the beam 125. For work of smaller size, however, it is usually desired to have the bar 159 approximately centered on the beam 125 and the member 141 correspondingly placed on the frame 101 in approximately the positions 15 indicated in Fig. 10.

Where the reproduction is to be on an enlarged scale rather than a reduced scale, the operation is simply reversed, the cutting tool being placed at 170 mounted in the spindle within the tube 20 167, and the tracing stylus being mounted in the spindle within the holder or socket 127.

In both reducing work and enlarging work, the tracing stylus and cutting tool remain at all times strictly perpendicular to the surfaces of 25 the tables 102 and 103, and may move straight up and down without any tilting, thus facilitating the making of vertical cuts or the proper finishing of vertical surfaces.

When making reproductions on the same size 30 or scale as the original, the tracing stylus may be mounted in the socket 128 on the beam 125, the cutting tool being placed on the spindle in the socket 127 so that both the tracing stylus and the tool are mounted on this parallel motion beam. 35 At this time, the lazytongs linkage may be entirely disconnected, but preferably it is employed as a convenient operating mechanism for moving the beam 125, since the operator can grasp the lower end of the tube 167 and use it as a handle 40 to move the beam 125 with less force than would be required if he grasped the tracing stylus directly. The position of the holder 128 on the beam 125 may be shifted laterally as desired, to place the tracing stylus at any desired distance 45 from the cutting tool.

It is thus seen that the machine in its preferred form, illustrated in Figs. 7 to 14, inclusive, is capable of making reductions, enlargements, and reproductions on the same scale as the original, and that at all times the work and the pattern are conveniently arranged close to each other, where the operator may observe both of them simultaneously. The work is on the same side of the fixed vertical pivot of the lazytongs linkage as the pattern, so that the movements over the surfaces of the work and pattern are not reversed, but correspond to each other in direction, and the pattern may be oriented in the same direction with the work, without having to be turned 180° relatively to the work, as in many prior machines. It will also be appreciated by those skilled in the art that many other important features and refinements are present in 55 this preferred form of machine, resulting in a particularly efficient, simple, and satisfactory machine for either engraving or copying or both.

Certain subject matter disclosed but not claimed herein is claimed in one or another of 70 three companion applications, Serial No. 202,567, for Driving means for engraving and copying machine; Serial No. 202,568, for Counterbalancing means for engraving and copying machines; and Serial No. 202,569, for Tool spindle for engrav- 75

ing and copying machines, all filed April 16, 1938, in the name of Kurt Zwick.

While certain embodiments of the invention have been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. An engraving or copying machine comprising a beam guided for free movement of translation in any direction in one plane and restrained against movement of rotation in said plane, socket means mounted on said beam for holding a cutting tool, a lazytongs pantograph linkage having a main pivot approximately perpendicular to said plane of free movement of said beam, said linkage having means for holding a tracing stylus at a point remote from said main pivot, and means operatively connecting said beam to said linkage at a point between said main pivot and said tracing stylus, so that movements imparted to said tracing stylus cause movements of said beam in the same direction but on a reduced scale.

2. An engraving or copying machine comprising a beam guided for free movement of translation in any direction in one plane and restrained against movement of rotation in said plane, a plurality of sockets on said beam, one of said sockets being adapted to hold a cutting tool and another of said sockets being adapted to hold a tracing stylus, a lazytongs linkage having a main pivot approximately perpendicular to said plane of movement of said beam, said linkage having means for holding interchangeably either a cutting tool or a tracing stylus at a point remote from said main pivot, and means operatively connecting said beam to said linkage at a point between said main pivot and said holding means on said linkage.

3. An engraving or copying machine adapted to reproduce work either on the same scale or on a reduced or enlarged scale, as desired, said machine comprising a beam mounted for free movement of translation in any direction in one plane and restrained against movement of rotation in said plane, means on said beam for holding a cutting tool and a tracing stylus, a lazytongs linkage having a main pivot, means on said linkage for holding either a cutting tool or a tracing stylus as desired, and means connecting said beam to said lazytongs linkage at a point between said main pivot thereof and said tool or stylus holding means thereof.

4. An engraving or copying machine comprising a member mounted for movement in a direction transverse to its length, a beam mounted on said member for movement in a direction longitudinally thereof, means on said beam for holding a cutting tool, a lazytongs linkage having a main pivot, means on said linkage for holding a tracing stylus at a point spaced from said main pivot, and means connecting said beam to said lazytongs linkage at a point between said main pivot and said means for holding a tracing stylus.

5. An engraving or copying machine comprising a beam mounted for free movement of translation in any direction in one plane and restrained against movement of rotation in said plane, means on said beam for holding a cutting tool, a lazytongs linkage having a main pivot, means on said linkage for holding a tracing stylus at a point spaced from said main pivot, a bar secured

to said beam and extending for a substantial distance in a general direction transverse to said beam, and means connecting said bar to said lazytongs linkage at a point between said main pivot and said stylus holding means, said connecting means being adjustable to any one of a plurality of different positions along said bar.

6. An engraving or copying machine comprising a beam mounted for free movement of translation in any direction in one plane and restrained against movement of rotation in said plane, means on said beam for holding a cutting tool, a lazytongs linkage having a main pivot, means on said linkage for holding a tracing stylus at a point spaced from said main pivot, a bar secured to said beam and extending for a substantial distance in a general direction toward and away from said main pivot, and means connecting said bar to said lazytongs linkage at a point between said main pivot and said stylus holding means, said connecting means being adjustable to any one of a plurality of different positions along said bar.

7. An engraving or copying machine comprising a frame member, a carrier pivotally connected to said frame member for oscillation about one axis, a lazytongs linkage mounted on said carrier for oscillation about a main pivotal axis substantially perpendicular to said first mentioned carrier axis, means on said lazytongs linkage for holding a tracing stylus, a beam mounted for universal movement of translation in all directions, means on said beam for holding a cutting tool, and means connecting said beam to said lazytongs linkage at a point between said main pivotal axis of said linkage and said means for holding a tracing stylus.

8. An engraving or copying machine comprising a frame member, a carrier pivotally connected to said frame member for oscillation about one axis, a lazytongs linkage mounted on said carrier for oscillation about a main pivotal axis substantially perpendicular to said first mentioned carrier axis, means on said lazytongs linkage for holding a tracing stylus, a slide mounted on said frame member for movement thereon in a direction substantially parallel to said main pivotal axis, a beam supported from said slide for movement in any direction in a plane substantially perpendicular to said main pivotal axis, means on said beam for holding a cutting tool, and means connecting said beam to said lazytongs linkage at a point between said main pivotal axis of said linkage and said means for holding a tracing stylus.

9. An engraving or copying machine comprising a frame member, a carrier pivotally connected to said frame member for oscillation about one axis, a lazytongs linkage mounted on said carrier for oscillation about a main pivotal axis substantially perpendicular to said first mentioned carrier axis, means on said lazytongs linkage for holding a tracing stylus, a slide mounted on said frame member for movement thereon in a direction substantially parallel to said main pivotal axis, a beam supported from said slide for movement in any direction in a plane substantially perpendicular to said main pivotal axis, means on said beam for holding interchangeably either a cutting tool or a tracing stylus, and means connecting said beam to said lazytongs linkage to move one from movements of the other.

10. An engraving or copying machine comprising a frame member, a carrier pivotally connected to said frame member for oscillation about one

axis, a lazytongs linkage mounted on said carrier for oscillation about a main pivotal axis substantially perpendicular to said first mentioned carrier axis, means on said lazytongs linkage for holding a tracing stylus, a slide mounted on said frame member for movement thereon in a direction substantially parallel to said main pivotal axis, a beam supported from said slide for movement in any direction in a plane substantially perpendicular to said main pivotal axis, means on

- 5 holding a tracing stylus, a slide mounted on said frame member for movement thereon in a direction substantially parallel to said main pivotal axis, a beam supported from said slide for movement in any direction in a plane substantially perpendicular to said main pivotal axis, means on said beam for holding a bar secured to said beam and extending for a substantial distance in a general direction toward and away from said main pivotal axis, and means shiftable to different positions along said bar for connecting said bar to said lazytongs linkage to move one from movements of the other.
- 10 11. An engraving or copying machine comprising a lazytongs linkage mounted for movement about a main pivotal axis and also mounted for bodily swinging movement about an axis substantially perpendicular to said main pivotal axis, a beam guided for universal movement of translation in any direction, means connecting said beam to said lazytongs linkage to move one from movements of the other, means on said beam for holding a cutting tool, a stylus guide, linkage means connecting said stylus guide to said beam so that said guide may move relatively to said beam in any direction in one plane and is restrained against movement out of said plane and against tilting movement, a tracing stylus mounted for movement in said stylus guide in a direction substantially perpendicular to the plane in which said stylus guide may move, and means pivotally connecting said stylus to said lazytongs linkage.

- 15 16. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, and means connected to said linkage at another point for holding a tracing stylus.

- 20 21. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, and means connected to said linkage at another point for holding a tracing stylus.

- 25 26. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, and means connected to said linkage at another point for holding a tracing stylus.

30 31. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, and means connected to said linkage at another point on the opposite side of said first point from said main pivot for holding a tracing stylus.

- 35 36. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, means connected to said linkage at another point for holding a tracing stylus, and means including a linkage connected to said beam for maintaining said last named stylus holding means in a substantially vertical position while allowing both horizontal and vertical movements thereof.

- 40 41. An engraving or copying machine comprising a frame, means with one or more substantially horizontal surfaces for supporting work and a pattern, a substantially vertical guideway on said frame, a slide movable substantially vertically along said guideway, a beam supported from said slide and guided for movement of translation in any direction in a substantially horizontal plane, means on said beam for holding a cutting tool for cooperation with work on said supporting means, other means on said beam for holding a tracing stylus for cooperation with a pattern on said supporting means, a carrier pivotally mounted on said frame for oscillation about a substantially horizontal axis, a pivot on said carrier substantially perpendicular to said horizontal axis; a lazytongs linkage mounted on said carrier pivot as a main pivot, a pivotal connection between said beam and one point of said linkage so that both horizontal and vertical movements of said point of said linkage cause corresponding movements of said beam, means for holding a tracing stylus, means including a universal joint for connecting said last named means for holding a stylus to said lazytongs linkage, and means for maintaining said last named means for holding a stylus in a substantially vertical position while allowing both horizontal and vertical movements thereof.

- 45 46. An engraving or copying machine comprising a frame, a lazytongs linkage mounted on said frame for extension and contraction movements and also for bodily tilting movements relatively to said frame, a stylus guide, means for maintaining said stylus guide in a fixed direction relatively to said frame while allowing free movement of said guide in all directions in a plane.

perpendicular to said fixed direction, stylus holding means mounted in said guide for movement therein in said fixed direction, and universal joint means connecting said stylus holding means to said lazytongs linkage.

5 17. An engraving or copying machine comprising a beam mounted for free movement of translation in any direction in one plane and restrained against movement of rotation in said plane, a lazytongs linkage, means connecting said lazytongs linkage to said beam to move one in accordance with movements of the other, said connecting means being shiftable to a plurality of different positions along said beam, and cutting tool means and tracing stylus means mounted on said beam and linkage.

10 18. An engraving or copying machine comprising a beam mounted for free movement of translation in any direction in one plane and restrained against movement of rotation in said plane, a lazytongs linkage, cutting tool means and tracing stylus means mounted on said beam and linkage, a guideway extending lengthwise of said beam, a connecting member mounted on said guideway for movement therewith to any one of a plurality of different positions, and means operatively connecting said linkage to said connecting member so that movements of said linkage will cause corresponding movements of said beam.

15 19. An engraving or copying machine comprising a beam mounted for free movement of translation in any direction in one plane and restrained against movement of rotation in said plane, a lazytongs linkage, cutting tool means and tracing stylus means mounted on said beam and linkage, a guideway extending lengthwise of said beam, a connecting member mounted on said guideway for movement therewith to any one of a plurality of different positions, said connecting member extending a substantial distance 20 in a general direction transverse to said beam, and means for operatively connecting said linkage to said connecting member at any one of a plurality of different positions along said connecting member, so that movements of said linkage will cause corresponding movements of said beam.

25 20. An engraving or copying machine comprising a frame, an elongated beam mounted on said frame for universal movement of translation in at least one approximately horizontal plane, a guideway extending approximately horizontally on said frame and approximately parallel to the length of said beam, a member mounted for movement along said guideway to any one of a plurality of different positions, a lazytongs linkage having a main substantially vertical pivot mounted on said member to move bodily therewith along said guideway, means for operatively connecting said linkage to said beam at any one 30 of a plurality of locations spaced along said beam, and tracing stylus means and cutting tool means associated with said linkage and said beam.

35 21. An engraving or copying machine comprising a frame, a guideway extending approximately horizontally on said frame, a member mounted for movement along said guideway to any one of a plurality of different positions, a lazytongs linkage having a main substantially vertical pivot mounted on said member to move bodily therewith along said guideway, a beam supported from said frame for free movement of translation in any direction in one plane and restrained against movement of rotation in said plane, cutting tool means and tracing stylus means mounted on said beam and linkage, a

guideway extending along said beam in a direction approximately parallel to said guideway on said frame, a connecting member mounted on said guideway on said beam for movement therewith to any one of a plurality of different positions, and means operatively connecting said linkage to said connecting member so that movements of said linkage will cause corresponding movements of said beam.

40 22. An engraving or copying machine comprising a beam mounted for free movement of translation in any direction in one plane and restrained against movement of rotation in said plane, cutting tool holding means mounted on said beam, and tracing stylus holding means also mounted on said beam, one of said holding means being mounted for movement along said beam to any one of a plurality of different positions at different distances from the other of said holding means.

45 23. An engraving or copying machine comprising a frame, a carrier mounted for upward and downward movement on said frame, a parallel motion beam mounted on said carrier to move upwardly and downwardly therewith, a cutting tool assembly mounted on said beam and shiftable therewith in any direction, a lazytongs pantograph linkage operatively connected to said beam to control the movements thereof, and adjustable abutment means for determining the lowermost position to which said carrier may move relative to said frame, thereby controlling the lowermost position of said cutting tool assembly.

50 24. An engraving or copying machine comprising a frame, a cutting tool assembly mounted for upward and downward movement relative to said frame and for movement to shift a cutting tool carried thereby in any direction in an approximately horizontal plane, an adjusting screw mounted on said frame to rotate relative thereto, said screw serving to limit downward motion of said assembly relative to said frame, and graduated scale means associated with said adjusting screw so that said screw may be readily set to various predetermined positions of adjustment.

55 25. An engraving or copying machine comprising a frame, a cutting tool assembly mounted for upward and downward movement relative to said frame and for movement to shift a cutting tool carried thereby in any direction in an approximately horizontal plane, an adjusting screw mounted on said frame to rotate relative thereto without longitudinal movement relative thereto, nut means threadededly engaged with said adjusting screw, means holding said nut means against rotation relative to said frame so that when said screw is rotated relative to said frame said nut means will not rotate therewith and will move longitudinally along said screw, and means on said assembly overlying said nut means to contact therewith and be stopped thereby when said assembly moves downwardly, so that the position of said nut means on said screw determines the lowermost position to which said assembly may move relative to said frame.

60 26. An engraving or copying machine comprising pattern and work table means extending substantially horizontally, frame means extending upwardly to an elevation above said table means, a beam supported from said frame means and guided for free movement of translation in any direction in at least one plane extending approximately horizontally above said work table means and restrained against movement of ro-

tation in said plane, means on said beam for holding a cutting tool to move bodily with movements of said beam over work held by said work table means, a lazytongs pantograph linkage supported from said frame means for movement in an approximately horizontal plane above said beam about an approximately vertical main pivot adjacent said frame means, a tracing stylus mounted on said linkage at a point remote from said main pivot for movement over a pattern held by said pattern table means, and means operatively connecting said linkage to said beam at a point between said tracing stylus and said main pivot, so that movements of said tracing stylus will cause corresponding movements on a reduced scale of said beam and of a cutting tool mounted thereon.

27. An engraving or copying machine comprising pattern and work table means extending substantially horizontally, frame means extending upwardly to an elevation above said table means, a beam supported from said frame means and guided for free movement of translation in any direction in at least one plane extending approximately horizontally above said work table means and restrained against movement of rotation in said plane, means on said beam for holding a cutting tool to move bodily with movements of said beam over work held by said work table means, a lazytongs pantograph linkage supported from said frame means for movement in an approximately horizontal plane above said beam about an approximately vertical main pivot adjacent said frame means, a tracing stylus mounted on said linkage at a point remote from said main pivot for movement over a pattern held by said pattern table means, said tracing stylus being movable upwardly and downwardly with respect to said frame means, guiding means mounted on said beam and flexible in an approximately horizontal direction and substantially rigid in an approximately vertical direction for guiding the upward and downward movements of said stylus, and means operatively connecting said linkage to said beam so that movements of said tracing stylus will cause corresponding movements of said beam and of a cutting tool mounted thereon.

28. An engraving or copying machine adapted to make reproductions on an equal scale and on a reduced scale and on an enlarged scale, as desired, said machine comprising a member mounted for movement in any direction to a large number of different positions each one of which is substantially parallel to the others, a reduction and enlargement pantograph linkage of the lazytongs type mounted adjacent said member, a plurality of holding means on said member, one of said holding means being adapted to hold a cutting tool and another of said holding means being adapted to hold a tracing stylus, holding means on said linkage adapted to hold either a cutting tool or a tracing stylus as desired, and means operatively connecting said linkage to said member at a point spaced from said holding means on said linkage, so that movements of said holding means on said linkage will cause movements of said holding means on said member and vice versa.

29. An engraving or copying machine adapted to make reproductions on an equal scale and on a reduced scale and on an enlarged scale, as desired, said machine comprising a member mounted for movement in any direction to a large number of different positions each one of

which is substantially parallel to the others, a reduction and enlargement pantograph linkage of the lazytongs type mounted adjacent said member, a plurality of holding means on said member, one of said holding means being adapted to hold a cutting tool and another of said holding means being adapted to hold a tracing stylus, holding means on said linkage adapted to hold either a cutting tool or a tracing stylus as desired, means operatively connecting said linkage to said member at a point spaced from said holding means on said linkage, and means for altering the point on said member at which said linkage is connected thereto.

30. An engraving or copying machine adapted to make reproductions on an equal scale and on a reduced scale and on an enlarged scale, as desired, said machine comprising a member mounted for movement in any direction to a large number of different positions each one of which is substantially parallel to the others, a reduction and enlargement pantograph linkage of the lazytongs type mounted adjacent said member, a plurality of holding means on said member, one of said holding means being adapted to hold a cutting tool and another of said holding means being adapted to hold a tracing stylus, holding means on said linkage adapted to hold either a cutting tool or a tracing stylus as desired, means operatively connecting said linkage to said member at a point spaced from said holding means on said linkage, and means for adjusting in each of two directions at a substantial angle to each other the point on said member at which said linkage is connected thereto.

31. An engraving and copying machine adapted to make reproductions on an equal scale and on an unequal scale, as desired, said machine comprising work table means, frame means having a portion projecting upwardly to an elevation above the top of said work table means at one side thereof, pattern table means on the same general side of said upwardly projecting portion as said work table means, so that an operator may readily observe objects upon both said work table means and said pattern table means without materially shifting his position, a beam overlying said work table means and mounted on said upwardly projecting frame portion for movement in any direction to a large number of different positions each one of which is substantially parallel to the others, a pantograph linkage of the lazytongs type supported from said upwardly projecting frame portion and mounted to swing about a main pivotal axis adjacent said frame portion and extending from said axis into overlying relationship to said pattern table means and work table means, means on said linkage for holding a tracing stylus in position to cooperate with a pattern held on said pattern table means, means operatively connecting said linkage to said beam at a point between said tracing stylus and said main pivotal axis so that movements of said tracing stylus will cause corresponding movements of said beam in the same direction on a reduced scale, means on said beam for holding a cutting tool in position to cooperate with work held on said work table means, and means for mounting a tracing stylus on said beam.

32. A construction according to claim 31, further including guiding means mounted on said beam for guiding a tracing stylus mounted on said linkage.

33. A construction according to claim 31, in

which said pantograph linkage is mounted for tilting movement about an axis lying approximately in a plane perpendicular to said main pivotal axis, and in which said tracing stylus mounted on said linkage is connected to said linkage by a flexible joint so that said stylus may tilt relative to said linkage.

34. A construction according to claim 31, in which said pantograph linkage is mounted for tilting movement about an axis lying approximately in a plane perpendicular to said main

pivotal axis, and in which said tracing stylus mounted on said linkage is connected to said linkage by a flexible joint so that said stylus may tilt relative to said linkage, and further including means mounted on said beam for holding said stylus mounted on said linkage always in a position substantially parallel to every other position thereof, notwithstanding tilting movements of said linkage.

KURT ZWICK. 10
